US0D1046829S

(12) **United States Design Patent** (10) **Patent No.:** **US D1,046,829 S**
(45) **Date of Patent:** **** Oct. 15, 2024**

(54) **MICROPHONE STAND**

(71) Applicant: **FUJIAN EASTWEST LIFEWIT TECHNOLOGY CO., LTD**, Fuzhou (CN)

(72) Inventor: **Feng Lian**, Fuzhou (CN)

(73) Assignee: **FUJIAN EASTWEST LIFEWIT TECHNOLOGY CO., LTD**, Fuzhou (CN)

(**) Term: **15 Years**

(21) Appl. No.: **29/932,714**

(22) Filed: **Mar. 15, 2024**

(51) **LOC (14) Cl. 14-01**

(52) **U.S. Cl.**

USPC **D14/229**

(58) **Field of Classification Search**

Primary Examiner — L. A. Grabenstetter

(57) **CLAIM**

The ornamental design for a microphone stand, as shown and described.

DESCRIPTION

FIG. 1 is a perspective view of a microphone stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a perspective view of the microphone stand where the microphone stand is in a first open state;

FIG. 10 is another perspective view of the microphone stand where the microphone stand is in a second open state;

FIG. 11 is an enlarged view of portion 11 shown in FIG. 1; and,

FIG. 12 is an enlarged view of portion 12 shown in FIG. 2. The dash-dash broken lines in the drawings depict portions of the microphone stand that form no part of the claimed design. The dot-dash broken lines represent boundaries of the enlarged portions and form no part of the claimed design.

1 Claim, 12 Drawing Sheets
